ADJUSTABLE INDICATOR FOR STOVE VALVES

Herbert M. Reeves, Kankakee, Ill., assignor to
 Florence Stove Company, Gardner, Mass., a
 corporation of Massachusetts

Application October 31, 1946, Serial No. 706,915

6 Claims. (Cl. 126—39)

1

The present invention relates to valve position indicating means for oil stoves and has especial reference to a low fire indicator for use under burner valves of oil cook ranges.

Because the quantity of oil required to maintain a low fire is small, the setting of a valve controlling the supply of oil if a stable low flame is to obtain is comparatively critical. Valves commonly used in oil stoves vary in performance because of individual peculiarities brought about in the process of their manufacture. Further, differences in the oil level will also be reflected in the flow of oil through a particular valve. Thus for each burner the optimum low-fire valve setting must be separately determined by experimentation.

One object of the present invention is to provide an adjustable valve position indicating means for oil stoves, that permits of ready adjustment to indicate a desired low-fire position of each burner valve as may be determined by trial.

A more specific object of the invention lies in the provision of means operatively associated with the stem of a stove burner valve and adjustable independently thereof whereby a desired setting of low-fire valve opening may be shown.

A further object is to provide a device of the aforementioned character which is inexpensive to manufacture, and which is simple and sturdy in construction.

The objects of the invention thus set forth, together with other and ancillary advantages, are attained by the construction and arrangement shown by way of illustration in the accompanying drawings, in which:

Figure 1 is a fragmentary perspective view of an oil cook range in which the present invention is incorporated.

Fig. 2 is a perspective view, partly in section, illustrating the invention as applied to a burner valve of an oil stove.

Fig. 3 is a front elevational view showing the elements of the device in the position occupied during adjustment.

Fig. 4 is a front elevation showing the components of the indicator set for operation.

While the invention is susceptible of various modifications and alternative constructions there is shown in the drawings and will herein be described in detail the preferred embodiment, but it is to be understood that it is not thereby intended to limit the invention to the form disclosed, but it is intended to cover all modifications and alternative constructions falling within

2

the spirit and scope of the invention as expressed in the appended claims.

For purposes of illustration, the invention has been shown as incorporated in an oil range having a vertical front panel 10 in front of which are located valve handles 12 for controlling the burner valves of the stove. It contemplates the provision of means disengageably connected to the valves to permit independent adjustment thereof for accurate indication of a desired low-fire setting whereby the valve can be readily reset to that position once it has been determined and the indicator has been adjusted to give such determination.

Referring particularly to Fig. 2, the preferred form of the invention is there shown as applied to a conventional needle type burner valve having an operating handle 12, a stem 14 and a body 16. Oil is supplied to the valve from a supply pipe 18 and leaves the valve by the way of a pipe 19.

In the illustrative embodiment, the valve position indicating means comprises a disk 20 rotatably supported behind and adjacent to the stove panel 10. So that the disk 20 will indicate a setting of the valve, a driving connection between the disk and the valve is provided. In the present instance the rotation of the disk is controlled by the rotation of the valve stem. To afford a non-slip driving connection between the disk 20 and the valve stem 14, a series of teeth 22 are formed in the peripheral edge of the disk, adapted to intermesh with similar teeth constituting a pinion gear 24 on the valve stem. Thus when the handle 12 on the stem 14 is turned in a counter-clockwise direction, the disk 20 will be rotated in a clockwise direction.

Indication of valve setting is given by a radially extending line or mark 26 located on the front surface of the disk 20. So that this mark can be viewed from the front of the panel 10, an opening 28 is provided in the panel which is so fashioned to afford a fixed reference, such as the pointer 29, with which the mark 26 can be aligned to accurately set the valve.

As hereinbefore mentioned, the proper setting of the valve is determined by experiment. After its position has thus been determined the indicator must be adjusted to show this position. For this purpose the driving connection between the disk 20 and the valve stem 14 is made disengageable by means readily accessible from in front of the stove burner 10. To this end, the disk 20 has fixed thereto a central operating knob 30, which extends forwardly through a vertically

elongated opening 32 in the panel 10, and the disk is mounted for movement in a direction transversely of the axis of the valve stem 14 into and out of engagement with the pinion 24 on the valve stem. In the present instance, the disk is mounted on a resilient support in the form of a U-shaped member 34 of spring wire. One leg 34a of the member 34 extends forwardly through the center of the disk 20 and into a recess 36 in the rear of the knob 30. Rearwardly of the disk, the leg 34a passes through a vertical slot 37 in a cross bar 38 of the stove frame. The other leg 34b also passes through the slot 37 and has its tip bent upwardly and inserted in a slot 39 which is also in the members 38. It will be seen that by this construction the support 34 is held against turning and that it acts to hold the disk 20 yieldably against the valve stem pinion 24. Preferably the disk 20 is held against the rear of the front panel 10 by a compression spring 40 encircling the leg 34a of the support 34 and positioned between the disk and the cross bar 38.

The adjustment of the novel indicating device will be apparent from the foregoing but can be summarized briefly as follows: When the proper low-fire position for any given valve has been determined by experimentation, the user merely raises the disk 20 by means of the knob 30 from engagement with the pinion 24 and the valve stem 14 (Fig. 3) and rotates the knob and disk until the mark 26 is alined with the pointer 29. The knob is then lowered to re-engage the disk with the valve stem pinion in proper indicating relation thereto as shown in Figs. 2 and 4.

I claim as my invention:

1. In an oil stove having a burner valve with a rotatable stem, an adjustable low-fire valve position indicator comprising, in combination, a disk having teeth on its peripheral edge, a pinion on said valve stem, and means operative to hold said disk teeth and said pinion in disengageable driving connection said means being yieldable whereby the position of said disk can be adjusted independently of said valve stem.

2. In a stove the combination of a panel, a burner valve, a rotatable stem for said valve and an adjustable low-fire position indicator for said valve including a disk positioned behind said panel and viewable therethrough, means secured to said disk and projecting through said panel by which the setting of said disk can be adjusted, and resilient holding means operable to urge said disk into driving engagement with said valve stem.

3. In a stove having a panel and a burner valve with a rotatable stem projecting through said panel, an adjustable valve position indicator comprising, in combination, a disk positioned behind

5 said panel and partially viewable therethrough, means fixed to said disk and projecting through said panel to permit adjustment of the position of said disk, yieldable means operative to urge said disk against said panel, and said disk having a disengageable driving connection with said stem.

4. In a stove having a panel, a burner valve with a rotatable stem projecting through said panel and an elongated opening in said panel adjacent said burner valve stem, an adjustable valve position indicator comprising, in combination, a disk positioned behind said panel and partially viewable therethrough, a knob fixed to said disk and projecting through said elongated panel opening to permit adjustment of the position of said disk and yieldable holding means operative to urge said disk in driving engagement with said valve stem, said means and said knob operating to permit movement of said disk into and out of engagement with said valve stem.

5. In a stove a brace member and a burner valve with a rotatable stem located adjacent said brace member, an adjustable valve position indicating means comprising, in combination, an indicator disk having a recess therein, and yieldable holding means operative to urge said disk in driving engagement with said valve stem, said holding means including a U-shaped length of resilient wire having one of its legs passing through said brace and inserted in said disk recess, and having its other leg secured to said brace member in a manner to prevent turning of the holding means.

35 6. In a stove, a burner valve with a rotatable stem and an adjustable valve position indicator comprising, in combination, indicating means including a gear element and yieldable holding means operative to urge said gear element in driving engagement with said valve stem, said holding means comprising a resilient U-shaped member having a fixed leg and a movable leg, said gear element being supported on the movable leg.
